 Philip R. M. Hunt

(57) CLAIM

The ornamental design for a shooting bench with a groove near edge of deck, as shown and described.

DESCRIPTION

FIG. 1 shows a back perspective view of the design. FIG. 2 shows a front perspective view of the design. FIG. 3 shows a side perspective view of the design; and, FIG. 4 shows a bottom perspective view of the design. The broken lines are for illustrative purposes only and form no part of the claimed design.
